UNITED STATES PATENT OFFICE.

WILLIAM EDENBORN AND GUSTAV GRIESCHE, OF ST. LOUIS, MISSOURI;
SAID GRIESCHE ASSIGNOR TO SAID EDENBORN.

BARB-WIRE MACHINE.

SPECIFICATION forming part of Letters Patent No. 270,646, dated January 16, 1883.

Application filed November 1, 1882. (No model.)

To all whom it may concern:

Be it known that we, WILLIAM EDENBORN and GUSTAV GRIESCHE, both of the city of St. Louis, in the State of Missouri, have invented a certain new and useful Improvement in Wire Barbing Machines, of which the following is a full, clear, and exact description, reference being had to the accompanying drawings, forming part of this specification, and in which—

Figure 1 is a side elevation of the machine. Fig. 2 is a top view, parts being broken away. Fig. 3 is an enlarged detail top view, parts broken away and part in section, showing the machine just after the device for feeding the wire from which the barbs are cut has made its return movement. Fig. 4 is a similar view, showing the said parts in their other position—that is, just as they have fed the wire, before returning. Fig. 5 is an enlarged detail side elevation. Fig. 6 is an enlarged transverse section taken on line 6 6, Fig. 3. Fig. 7 is an enlarged transverse section taken taken on line 7 7, Fig. 3. Fig. 8 is an enlarged end view of the barb-former, showing its position before making the bend. Fig. 9 is a similar view after the barb is formed. Fig. 10 is a detail longitudinal section taken on line 10 10, Fig. 8. Fig. 11 is a similar view taken on line 11 11, Fig. 9. Fig. 12 is an end elevation of the machine, viewing it from the front, with two of the supporting-legs broken away. Fig. 13 is a vertical section taken on line 13 13, Fig. 3, viewing it from the rear, with such parts of the machine removed as are not desired to be shown. Fig. 14 is a front elevation of the shears or knives for cutting the barbs. Fig. 15 is a side elevation of same. Fig. 16 is a top view. Fig. 17 is a bottom view. Fig. 18 is an enlarged perspective view of the shears, showing their position just before cutting the barbs. Fig. 19 is a similar view, showing their position just after cutting. Fig. 20 is an enlarged top view of the clamp for feeding the barb-wire, showing the clamping-jaws open, which is their position while the clamp is making its backward movement. Fig. 21 is a similar view, showing the jaws closed upon the wire, which is their position as the clamp moves toward the cutter. Fig. 21^a is a

vertical longitudinal section of the clamp. Figs. 22 and 23 are diagrams showing in side elevations and in different positions the device for carrying the main wire toward the spool in such a manner that while it is fed continuously to the spooling mechanism, yet it is allowed before reaching this point to remain still at intervals of sufficient length to have the barbs applied. Fig. 24 is an enlarged perspective view of the barb-former, showing the finger in its outer position. Fig. 25 is a similar view, showing the finger in its inner position. Fig. 26 is a perspective view of a piece of the barbed wire.

Our invention relates to a machine for putting barbs on wire for fencing purposes.

Our invention consists in certain novel features hereinafter fully described and claimed.

Referring to the drawings, A represents the table of the machine, and A' the supporting-legs.

B represents the main shaft of the machine, journaled in boxes B', secured to the table. On one end of this shaft is a driving-pulley, B², and a cog-wheel, B³, the latter of which engages with a similar wheel, C', on the shaft of the spooling apparatus C, in which nothing new is claimed. On the other end of the shaft B is a cog-wheel, D, which engages with a pinion, D', on the hollow shaft D² of the barb-former, which is journaled in suitable boxes, D³, secured to the frame A, the tops of the boxes being removed in Fig. 3 and the barb-former shown in horizontal section.

The main wire E, from a suitable reel, E', passes through the hollow shaft, and the shaft is of different diameters, it being considerably the largest at its inner end, where it is channeled to receive the forming-finger F, which has a pin, F', on its outer end. After inserting the finger, the channel is closed above it by a dovetailed piece, F², which holds the finger in place. This end of the shaft is also bored out to receive a bushing, G, which has a conical outer end, (see Figs. 24 and 25,) for the purpose hereinafter explained, and it has a central opening, through which the main wire passes. As the finger finishes the formation of the barb it has an end-wise motion imparted to it, which causes it to recede into the hollow shaft, out of contact with

the wire, while the shaft continues to revolve, and immediately after it recedes it is thrust again to its outer position, ready to form another barb, the main wire in the meantime having 5 been moved along the desired distance, as herein-after described. This reciprocating motion is given to the finger by the following means:

H is a collar fitting loosely over the reduced or smaller portion of the shaft, and is connected with the finger by means of a set-screw, H', (see Figs. 3 and 6,) or by other suitable means. The collar is grooved to receive an annular ring or band, H², to which the arms J' of one end of a lever, J, are secured. The 15 lever is fulcrumed to a post, J², secured to the frame A, and its other end works in a groove, I', of a collar, I, secured to the end of the shaft B. The outer wall of the groove I' is provided with a projection, I², and the inner wall with 20 a corresponding notch, I³, (see Figs. 3 and 4,) which, coming in contact with the end of the lever, moves the collar H outward, as shown in Fig. 4, causing the projecting part of the finger to recede into the shaft, as stated, and 25 then as the projection I² leaves the end of the lever it (the lever) is moved to its other position, as it fits the groove snugly, throwing the finger to its working position. It will thus be seen that the finger has a continual revolving 30 and an intermittent reciprocating motion imparted to it.

We will now describe the device for intermittently feeding the wire from which the barbs are cut.

35 K is a block supported by and working in a suitable groove in the table A. The groove admits of an end-play of the block, and is lettered K'.

K² K² are jaws pivoted to the top of the 40 block, as shown, and having their rear ends so formed that a V-shaped opening is left between them, and their faces are notched or serrated.

L represents a wedge, which rests and has a limited end movement on the block K, its 45 inner end fitting between the rear ends of the jaws. The top of the block is formed with a flange around the outside, forming a cup, in which the jaws and wedge fit.

M is a lever, pivoted at M' to the top of the 50 table, and connected at one end by means of an arm or link, M², to the wedge L. The other end of this lever is connected by means of a link, M³, to one end of another lever, N, which is pivoted at N' to the table, and which has on 55 its other end a friction-roller, N², which bears against an eccentric, N³, on the shaft B. With this connection between the sliding block K and the shaft B, it will be seen that the former will be moved inward each time the salient 60 part of the eccentric N³ bears against the friction-roller N², the wedge L first being moved inward, as it connects with the arm M, as described, pressing the notched ends of the jaws against the wire, which passes between them, 65 as shown in Fig. 3, and shown plainly in Figs. 20 and 21, and thus the wire is moved toward

the main wire with the block the necessary distance to give wire enough for one barb. The wire passes through the flanges of the ends of the block and through the wedge, as shown in 70 Figs. 20, 21. When the block has thus been moved inward the salient part of the eccentric N³ is of sufficient length to hold it there until the finger has given the barb wire, with which it then comes in contact, one bend around the 75 main wire, and then the eccentric suddenly leaves the arm N, and a suitable spring, O, bearing against the lever M, (see Figs. 3 and 4,) forces the wedge L back against the rear flange of the block, which loosens the grip of the 80 clamps upon the wire, and then, as the wedge cannot move back farther, the block is carried outward, the wire slipping through it, for, as before stated, it has been made fast to the main wire.

We prefer placing springs P P between the side flanges of the block and the rear ends of the jaws, (see Figs. 20 and 21,) which take the bearing of the notched ends of the jaws from the wire as soon as the wedge has been forced back; but these springs are not absolutely necessary, as the jaws would slip over the wire without them, though they would bear slightly against it.

The ends of the levers M and N are adjustably connected together, preferably by means of bolts M⁴ and N⁴ passing through slots M⁵ and N⁵. (See Figs. 3 and 4.) This adjustable connection gives means for changing the movement of the block, and consequently the 100 amount of wire fed at each operation. The barb-wire passes beneath the main wire, and the finger, coming against its free end from beneath, bends it around the main wire twice, as shown in Fig. 11, and then retreats into the 105 hollow shaft, as before described. Immediately after the block K has made its return movement, which takes place when the finger has bent the barb-wire around the main 110 wire once, and while the finger is completing its work, the barb is cut from the main body of the wire by knives constructed as follows:

Q is an inclined lever, pivoted to a post, Q', by means of a bolt, Q³, passing through a hole, Q², of the lever. The post is secured to the 115 top of the table. To the lower end of the lever (see Figs. 18 and 19) are secured a knife, Q⁴, and a guide-block, Q⁵. The barb-wire passes through this guide-block, and also through the lower end of the knife, as shown 120 by dotted lines, and the knife has a beveled edge, which works against the beveled end of a stationary knife, R, secured to the table A by means of a plate, R', or by other suitable means. The hole through which the wire 125 passes is so located that the wire will come out through the bevel-edge of the knife Q⁴. This knife has an intermittent circular motion imparted to it by means of the upper end of the pivoted lever, extending over the shaft B 130 and being struck by an eccentric cam, S, (see Fig. 15,) on the shaft B. As the cam strikes

the lever it lowers the end to which the knife is secured, imparting the said circular motion to the knife, which carries the wire down upon the stationary knife, whose sharp edge cuts it, giving to the barb the desired sharp point. The knife Q^4 works in the space Q^6 (see Figs. 3, 10, and 11) between the end of the hollow shaft D^2 and the stationary knife R . To force the wire over the stationary knife, (see Fig. 11,) the conical end of the bushing G , before mentioned, is employed. As the finger wraps the barb-wire around the main wire twice, and as there is only room enough for one bend of the wire between it, when in its normal position, and the end of the bushing, it will be seen that the second bend will move the first bend forward by wedging between it the inclined face of the bushing, forcing the wire over the stationary knife before the knife Q^4 descends. Not only does the bushing force the wire over the knife R , but by this lateral movement binds it in the opening of the knife Q^4 , thereby enabling the knife to cut it more easily. As soon as the cam S operates the lever it leaves it, and the upper end of the lever is thrown down, thereby raising the knife Q^4 by means of its own weight, assisted by a spring, Q^7 , secured to the upper end of the post Q^8 , and bearing against a projection, Q^9 , on the upper end of the lever. In order that the lever will not bear or be pressed upon the shaft by the spring Q^7 , we secure an arm, Q^{10} , to the end of the lever, or to the block or projection Q^8 , which, when the lever is not raised by the cam S , rests upon the table, as shown in Fig. 5, holding the lever up out of contact with the shaft B . As soon as the finger has completed the barb and the knives cut it off the main wire is carried forward the proper distance by mechanism which we will now describe.

The wire from the barbing device passes over a wheel or drum, T , between it and a wheel or drum, T' , and then beneath the wheel or drum T' , from whence it passes to the spooling apparatus over the common vibrating wheel, U , which feeds it uniformly to the spool. The top of the wheel T works through a slot, T^2 , of the table, so that its periphery is on a line or nearly on a line with the barbing device. The wheels are preferably formed with circumferential grooves $T^3 T^4$, and their peripheries provided with teeth or notches, which engage the barbs on the wire which fits in the grooves, thus giving to the wire a positive forward motion. If these wheels $T T'$ were both stationary, the main wire, power being applied to the wheels, would be moved continuously forward before reaching the wheels as well as after it leaves them; and to so arrange these wheels or their equivalents that the wire will be fed to the spool continuously and at a uniform speed, while in advance of the wheels it is allowed to stand still at intervals of sufficient length to have the barbs applied, is one of the principal objects of our present inven-

tion. The means we have shown of accomplishing this end is: The wheel T' is rigidly secured to a shaft, V , which is journaled in suitable boxes, V' , suspended by hangers V^2 , 70 secured to the bottom of the table A . Power is applied to this shaft, preferably, by means of a cog-wheel, V^3 , thereon engaging with a worm, V^4 , on a shaft, V^5 , journaled in boxes V^6 , suspended from the bottom of the table by 75 means of hangers V^7 . On one end of the shaft V^5 is a pinion, V^8 , engaged by a cog-wheel, V^9 , on one end of a shaft, V^{10} , journaled in boxes V^{11} , suspended from beneath the table by 80 means of hangers V^{12} . On the other end of 85 this shaft V^{10} is a cog-wheel, V^{13} , similar to that V^9 , which engages with the wheel D on the shaft B . Thus the wheel T' , which carries the main wire forward, is driven from the main shaft of the machine. The wheel T is 85 journaled on a short axle, W , on the upper end of an arm, W' , supported by the shaft V . (See Figs. 22 and 23.) The arm W' is connected by a suitable link, W^2 , to the lower portion of a lever, W^3 , which passes up through and is pivoted to the table A at W^4 , and whose upper end has a lateral projecting pin, W^5 , which works in a groove, W^6 , of a collar, W^7 , secured to the shaft B . The groove passes spirally around the collar until it has about surrounded 90 it, and then with a sharp change passes in the other direction, as shown in Fig. 3. As the pin works in this groove, it will be seen that the lower end of the lever W^3 will be gradually moved toward the front end of the machine, carrying the wheel T with it, and then, when the pin comes to the change in the direction of the groove, the lower end of the lever and wheel will be forced with a quick movement in the other direction—that is, away from 95 the front end of the machine. The machine has its different parts so arranged that this quick forward movement of the wheel T occurs just after each barb has been completed, and it carries enough of the main wire forward to bring the next barb in the proper place. Then, as the wheel T moves slowly backward, the spool takes up the slack beneath. 100 We prefer to assist the quick forward movement of the wheel T by a spring, X , connecting the upper end of the arm W' with the bottom of the table, back of the wheel. The arm W' and the lower end of the lever W^3 are adjustably connected by the bolts securing the link W^2 thereto, passing through slots $W^8 W^9$, 105 as shown in Figs. 5, 22, and 23.

If it is desired to make twisted wire on the machine, as would generally be the case, the plain wire is taken from a spool, Y , secured to the front legs A' of the machine, (see Fig. 1,) 110 and joins the main wire at the wheel T , from where they go on together, and are twisted by the spooling apparatus, as usual.

If desired, the barb-wire need not pass through the knife Q^4 , but the knife be placed 115 high enough for the wire to pass beneath its lower end.

We claim as our invention—

1. In a wire-barbing machine, the wheels for carrying the main wire or wires forward, having power applied thereto and so arranged that one of them will have a vibrating motion imparted to it in the direction of the travel of the main wire or wires, in combination with a suitable device for giving the said vibrating movement to one of the wheels, for the purpose of giving an intermittent movement to the said wire or wires at the point of attachment of the barbs while it or they are fed continuously to the spooling apparatus, a suitable mechanism for feeding the wire from which the barbs are cut at stated intervals, mechanism for forming the barbs upon the main wire, mechanism for cutting the barbs off after being secured to the main wire, and a suitable spooling apparatus, substantially as set forth.
2. In a wire-barbing machine, the wheels for carrying the main wire or wires forward, one arranged above the other, and means for applying power to the lower wheel, the upper wheel mounted upon a suitable arm, which is connected by a suitable mechanical means with an eccentrically-grooved collar on the main shaft of the machine, whereby a vibrating movement in the direction of the travel of the main wire is imparted to the upper wheel for the purpose of giving an intermittent movement to the main wire at the point of the attachment of the barbs while it is fed continuously to the spooling apparatus, in combination with a suitable mechanism for feeding the wire from which the barbs are cut at stated intervals, mechanism for forming the barbs upon the main wire, mechanism for cutting the barbs off, and a suitable spooling apparatus, substantially as set forth.
3. In a wire-barbing machine, the wheels for carrying the main wire or wires forward, suspended beneath the table, one above the other, and means for applying power to the lower one, and the upper one journaled on an arm which has capability for movement in the direction of the travel of the main wire, and connected by a suitable link to the lower end of a lever which is pivoted to the table of the machine, and having a pin on its upper end, which works in an eccentric groove of a collar secured to the main shaft of the machine, thereby giving a back-and-forth movement to the upper wheel in the direction of the travel of the main wire for the purpose of imparting an intermittent movement to the main wire at the point of the application of the barbs while a continual feed is given to the spooling apparatus, the said device in combination with a suitable mechanism for feeding the wire from which the barbs are cut at stated intervals, a mechanism for forming the barbs upon the main wire, a mechanism for cutting the barbs off, and a suitable spooling apparatus, all substantially as set forth.
4. In a wire-barbing machine, a finger for forming the barbs upon the main wire, secured within a non-reciprocating revolving hollow shaft, through which the main wire passes, wherein it has an intermittent end movement imparted to it through means of a suitable mechanical device connecting it with the main shaft of the machine, the forming-pin on the end of the finger being to one side of the center of the hollow shaft, the finger thus having a compound continual revolving and intermittent reciprocating movement imparted to it for the purpose of first forming the barb around the main wire, and then being withdrawn from it, in combination with suitable mechanism for intermittently feeding the wire from which the barbs are cut, suitable mechanism for cutting the barbs off, suitable mechanism for intermittently moving the main wire forward, and a suitable spooling apparatus, substantially as set forth.
5. In a wire-barbing machine, a finger for forming the barbs upon the main wire, secured within a hollow revolving shaft, through which the main wire passes, wherein it has an intermittent end movement imparted to it by means of a collar, to which it is secured, surrounding and having an endwise movement upon the hollow shaft, and a lever which is fulcrumed to the table of the machine and connected by one end to the said collar in such a way as not to prevent the turning of the collar with the shaft, its other end working in an annular groove of a collar secured to the end of the main shaft of the machine, where it is struck by a projection on the side of the groove to operate the finger at the proper time, thereby causing it to recede into the hollow shaft, the forming-pin on the end of the finger being to one side of the center of the shaft, the finger thus having a compound continual revolving and an intermittent reciprocating movement imparted to it for the purpose of first forming the barb around the main wire, and then being withdrawn from it, in combination with a suitable mechanism for intermittently feeding the main wire forward, a mechanism for feeding the wire from which the barbs are cut at stated intervals, a mechanism for cutting the barbs off, and a suitable spooling apparatus, substantially as set forth.
6. In a wire-barbing machine, the bushing secured in the end of the hollow shaft, and having a conical outer end for the purpose of forcing the wire, as the barb is formed, over the knives, substantially as set forth.
7. In a wire-barbing machine, the combination, with a suitable mechanism for carrying the main wire forward at stated intervals, a mechanism for forming the barbs upon the main wire, and a mechanism for cutting the barbs off, of a mechanism for carrying the wire from which the barbs are cut at stated intervals, consisting essentially of a block supported by and having an end movement upon the table of the machine, having upon it clamping-jaws and a sliding wedge, the latter of

which is connected by a suitable link to one of a pair of levers, which are connected together and pivoted to the table, and which are operated upon by an eccentric cam on the main shaft to carry the sliding block inward, and by a suitable spring to move the block outward, substantially as set forth.

8. In a wire-barbing machine, the combination, with a mechanism for feeding the main wire forward at stated intervals, mechanism for placing the barbs upon the main wire, and mechanism for feeding the wire from which the barbs are taken at stated intervals, of a stationary knife secured to the table of the machine, a moving knife secured to the lower end of a pivoted lever, which extends above and is operated by an eccentric cam on the main shaft of the machine, as described, and a guide-

block, which is also secured to the lower end of the pivoted lever, and through which the 20 barb-wire passes, substantially as set forth.

9. In a wire-barbing machine, the pivoted lever which carries the moving knife and guide-block, having an arm secured to its upper end, which rests upon the table of the machine when 25 the lever is not raised by the eccentric cam on the main shaft, thereby keeping the lever out of contact with the said shaft, in combination with a spring which bears upon the lever to assist in raising the knife, substantially as set 30 forth.

WILLIAM EDENBORN.
